UNITED STATES PATENT OFFICE.

ROMAIN MARTINET AND ADOLPHE DULAC, OF GRENOBLE, FRANCE.

APPARATUS FOR DYEING HIDES AND SKINS.

No. 823,539.

Specification of Letters Patent.

Patented June 19, 1906.

Application filed March 6, 1906. Serial No. 304,465.

To all whom it may concern:

Be it known that we, ROMAIN MARTINET and ADOLPHE DULAC, citizens of the French Republic, residing at Grenoble, Isère, France, have invented certain new and useful Improvements in Apparatus for Dyeing Hides and Skins, of which the following is a specification.

This invention relates to an improved rotary apparatus for dyeing hides and skins in which the process of dyeing substantially comprises four successive operations—namely, first, the treatment with mordant; second, the dyeing proper; third, the operation of fixing or “striking;” fourth, the operation of rinsing or washing.

The liquid dye and other chemical solutions used are applied in the form of spray by means of sprayers to which the respective liquids are supplied by means of pumps provided with valves which allow the unused liquids to flow back to the respective receptacles. These pumps are of known construction and do not form part of the present invention.

The hides or skins to be dyed are placed on a circular table which is preferably divided into six compartments; but a larger or smaller number of compartments can be used, if desired. The said table is intermittently revolved with intervals of rest after each sixth of a revolution. During each interval of rest an attendant places an undyed hide in one of the compartments. During the next interval of rest this hide is acted on by a mordant supplied by means of a sprayer. Thereupon the said hide is moved by the table into a position in which it is during the third interval of rest acted on by the sprayer which supplies liquid dye. During the fourth interval of rest the dye applied to the hide is preferably allowed to soak into the latter without subjecting the said hide to further treatment; but in some cases the said interval can be used for repeating the application of dye by using dye of the same color as before or of a different color. During the fifth interval of rest the hide is subjected to the action of a solution for striking or fixing the dye, and during the sixth interval of rest another attendant rinses and energetically works the hide and removes it from the table.

The improved apparatus is illustrated in the annexed drawings, in which—

Figure 1 is a vertical section thereof. Fig.

2 represents the mechanism for operating the rotary table and the cocks or valves of the sprayers. Fig. 3 represents, on a larger scale, the cam which serves for the automatic control of the said valves or cocks; and Fig. 4 is a plan view of a detail of the sprayer-controlling mechanism.

A represents the circular table, which is divided into six compartments by means of walls or partitions B. The upper surface of the table is convex and covered with a sheet of lead A', having a circular flange at its circumference. Each compartment communicates with a duct or channel C for the discharge of the used liquids. The latter can, if desired, be collected in separate receptacles in order to be used again. The table has a central aperture and is supported by radial arms D of U-section fixed to a suitably flanged hub E, rotatable on a pillar F. The hub E is integral with a sleeve E', to which is fixed a bevel-wheel G, meshing with a pinion G', fixed to a shaft H, adapted to be intermittently rotated by means of the driving mechanism, which will now be described. The said driving mechanism comprises a worm-wheel I, fixed to the shaft H and in gear with a worm I' on a shaft I². The latter is mounted in suitable bearings and is provided with a fixed pulley J, a loose pulley J', and a loose pulley J², integral with a step-pulley J³. The pulleys J, J', and J² are adapted to be driven by means of a belt K, and the step-pulley J³ is connected, by means of a belt, with a step-pulley L, fixed to a shaft M, provided with a worm N, meshing with a worm-wheel N'. A grooved pulley O, fixed to the shaft M, is connected, by means of a cord O', with a group of pulleys O², revoluble on the pillar F, the said cord passing over a guide-pulley O². By means of the pulleys O² curvilinear motion is imparted to the sprayers in the manner which will be described hereinafter.

During the rotation of the worm-wheel N' a projection P, fixed to the lateral surface of the said wheel, comes into contact with a lever Q, pivoted at Q', so that during a portion of each revolution of the wheel the said lever is operated by the said projection, the movement of the lever being transmitted, by means of a connecting-rod R, to a lever S, which is pivoted at S' and one end of which engages a slide T for the purpose of shifting the belt K. The slide T is movable on a fixed plate T' and

is guided by means of studs T^2 , which extend through slots formed in the slide. To the slide T are fixed two arms U , between which passes the driving-belt K , and the slide is engaged by a lever V , which is pivoted at V' and adapted to be operated by projections X , fixed to the under surface of the table A , so that the belt K is shifted each time the table makes one-sixth of a revolution. Since the table A is in most cases of considerable diameter, it is preferably supported by means of a series of rollers Y , traveling in a circular race Z of U-shaped cross-section supported by pedestals Z' .

15 It is essential that the sprayers should only be in action intermittently during the periods at which the table is stationary. During the rotation of the table the sprayers must be put out of action. This is effected in the following manner: To the hub E is fixed a sleeve a , to the upper end of which is fixed a cam b , Figs. 1 and 3. A short distance above the said cam b a plate or spider c is mounted on the pillar F . The arms of the said spider, 20 which are preferably ribbed, are provided with central slots c' . In each of the said slots c' there is slidably a vertical rod d , which serves as an axle for a roller d' , the latter being kept in contact with the cam b by means of a spring e , bearing against a bail g , connected with the said axle. The lower ends of the axles d are guided by means of a slotted plate f . To each bail g there is fixed a curved rod g' , connected to the lever h of a cock h' , adapted to control one of the pipes i , which supply the mordant, dye, and other liquids used for treating the hides. Each of the said pipes is provided with an additional cock j , adapted to be operated, if necessary, by means of a handle j' , but normally the cocks j remain open. To the lower end of each pipe i a tube k , terminating in a rose k' , is connected by means of an india-rubber union, so that the said tube is movable relatively to the pipe i and can be caused, by means of a cam l , to travel through a sinuous path substantially resembling in outline one of the hides to be treated. For this purpose the tube is connected with a rod n , on which is mounted a roller kept in contact with the cam l by means of a spring m , connected with the said rod, the latter being connected with a pulley o , revolvable on the pipe i and adapted to be driven by means of one of the central pulleys O^3 . The pipe i and sprayers k k' are supported by means of suitable framework p with braces and stays to afford the necessary rigidity and strength. The pillar F is preferably made hollow in order that it can contain the pipes i' , which supply the mordant, dye, fixing liquid, water, or the like to the pipes i . This arrangement is, however, not essential, inasmuch as the said liquid can, if desired, be supplied by means of conduits arranged above the apparatus or in 25 any other suitable position.

The action of the apparatus is as follows: In the position shown in Figs. 1 and 2 the driving-belt K drives the pulleys J^2 , J^3 , and L , so that the shaft M is revolved and operates the worm N and the pulley O . The latter operates the pulleys O^3 and o , so that all the sprayers k k' are caused to act on the hides placed on the table A , the cocks h' being at this stage of the operation open. The rotation of the worm N and worm-wheel N' causes the projection P to act on the levers Q and S , so that the slide T is operated and shifts the belt K , by means of the arms U , from the pulley J^2 to the loose pulley J' and thence to the fixed pulley J , so that the shaft I^2 is driven. The latter transmits its movement by means of the worm I' and worm-wheel I to the shaft H , pinion G' , and bevel-wheel G , so that the table A is rotated, together with the cam b , and the latter operates the rods g' in such a manner that the cocks h' are closed. Meanwhile the cessation of the rotation of the shaft M causes the movement of the sprayers to be discontinued. When the table A has made one-sixth of a revolution, one of the projections X operates the lever V and the slide T in such a manner that the belt K is shifted back to the pulley J^2 , the rotation of the pulley J and shaft I^2 being stopped by means of a suitable brake q . At this stage of the operation the position of the cam b is such that the cocks h' are opened, so that the sprayers act on the hides and continue in action until the projection P again causes the table to rotate. The loose pulley J' allows of putting the apparatus out of action without stopping the driving-belt, and a handle r allows of operating the slide T by hand, if necessary. It is obvious that the intermittent rotation of the table and action of the sprayers can also be produced by other mechanical means—for instance, by means of toothed wheels provided with gaps or by means of a cam controlling a bifurcated lever adapted to shift the driving-belt. The essential features of the action are the intermittent rotation of the table A and the alternate opening and closing of the cocks controlling the sprayers. The devices by means of which this action is produced can be varied according to the particular circumstances and requirements of each case.

What we claim as our invention, and desire to secure by Letters Patent of the United States, is—

1. In a dyeing apparatus the combination of a table divided into a plurality of compartments for reception of the articles to be treated and adapted to be intermittently rotated through suitable fractions of a revolution, a plurality of sprayers adapted to discharge into said compartments, means for conveying various liquids to said sprayers, cocks controlling the latter and means whereby said cocks are automatically opened when

the table is at rest and closed when the table rotates substantially as described.

2. In a dyeing apparatus the combination of a table divided into a plurality of compartments for reception of the articles to be treated and adapted to be intermittently rotated through suitable fractions of a revolution, a plurality of sprayers adapted to discharge into said compartments, means for conveying various liquids to said sprayers, cocks controlling the latter, means whereby said cocks are automatically opened when

the table is at rest and closed when the table rotates and means for imparting curvilinear movement to the sprayers while the aforesaid cocks are opened substantially as described. 15

In witness whereof we have signed this specification in the presence of two witnesses.
